(57) **CLAIM**

The ornamental design for a thermal wrap, as shown and described.

DESCRIPTION

FIG. 1 is a front elevation view of a thermal wrap showing my new design with a gel-liquid insert removed from the thermal wrap;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is an isometric view thereof.
